UNITED STATES PATENT OFFICE.

PARK A. HERR, OF HILLSIDE, NEW JERSEY, ASSIGNOR TO THE SINGER MANUFACTURING COMPANY, A CORPORATION OF NEW JERSEY.

BOBBIN-WINDING MACHINE.

Application filed July 29, 1918. Serial No. 247,103.

To all whom it may concern:

Be it known that I, PARK A. HERR, a citizen of the United States, residing at Hillside, in the county of Union and State of New Jersey, have invented certain new and useful Improvements in Bobbin-Winding Machines, of which the following is a specification, reference being had therein to the accompanying drawings.

10 This invention relates to machines for winding thread upon bobbins one after another without stopping its operation.

It aims to improve machines of the type mentioned heretofore in use primarily to 15 better their speed and reliability.

To attain high speed in operation it aims 20 to provide a new and improved organization in which each of two separable rotary driving or clamp-heads is positively and continuously driven without interruption of their rotation while a filled bobbin is being discharged and an empty bobbin placed between them. To attain high speed as well as reliability in operation it provides devices insuring a substantially simultaneous 25 parting of the thread between a filled bobbin and the supply and gripping of the thread end between an empty bobbin and a displaceable driving head at the commencement 30 of a winding operation. Thus it aims to reduce the time interval between the completion and commencement of thread winding operations and to reduce the waste of thread. It seeks also to improve the means 35 for temporarily holding and disposing of a filled bobbin. To reduce the care and attention required of an operator, it aims to provide a magazine or hopper feed which is capable of handling any number of bobbins 40 without jamming or choking and consequent interruption of successive winding operations.

To the attainment of the ends above mentioned, the invention comprises essentially a 45 pair of rotary clamp-heads one of which is movable or shiftable axially relative to the other to release and receive filled and empty bobbins respectively and both of which are driven continuously and positively. The 50 main-shaft of the machine from which both heads are driven positively is provided with a worm and when the thread on the bobbin being wound accumulates as much as de-

sired a finger, spring-pressed lightly thereagainst, is shifted sufficiently to release a 55 movable section of a worm wheel arranged below the worm on the main-shaft, and to allow the movable section under the action of its own spring to intermesh with the worm on the main-shaft completing the continuity of the worm-wheel and starting operation thereof. To the worm-wheel a number of cams are connected, and from these cams a hopper feeding mechanism, a bobbin transferring mechanism, a thread severing 60 mechanism and a thread holding mechanism are operated in proper sequence to discharge a filled bobbin and insert an empty bobbin without stopping the rotation of the main-shaft and clamp-heads directly geared 65 thereto.

The invention is illustrated in the accompanying drawings in which Fig. 1 is a front elevation of a machine in which the invention is embodied with the hopper and chute 75 omitted. Fig. 2 is a rear elevation with the hopper and chute in position. Fig. 3 is a plan view partly in section through the main-shaft of the machine. Fig. 4 is a detail partly in section of the thread-cutting 80 mechanism. Fig. 5 is a transverse vertical sectional detail through the carriage for the displaceable clamp-head. Fig. 6 is a longitudinal vertical section through the carriage. Fig. 7 is a left hand side elevation 85 of the machine. Fig. 8 is a right hand side elevation of the machine. Fig. 9 is a transverse vertical section through the space between the operable clamp-heads viewed from the left hand end of the machine. Fig. 10 90 is a sectional detail through the worm and worm-wheel. Figs. 11, 12 and 13 are details of a controlling finger and whose end rests upon the accumulated bobbin-thread. Fig. 14 is an inside view of the hopper and cone-shaped agitator therewithin, the cover-portion of the hopper being removed. Fig. 15 is a bottom plan view of the hopper and its driving mechanism. Fig. 16 is a detail in cross-section of a one-way driving connection for intermittently rotating the hopper. Fig. 17 is a vertical section through the hopper and receiving end of the chute. Fig. 18 is a front side elevation of the mechanism 100 for increasing the spring-pressure with which an empty bobbin is initially gripped.

Fig. 19 is a detail plan view of the latch and its controlling lever and finger.

The various trains of mechanism are supported by a frame of the form illustrated in 6 the drawings and its stationary parts are everywhere indicated by the numeral 1.

A main driving shaft 2 is supported in the bearings 3 and has secured thereto a rotary clamp-head 4, a worm 5 and a driving pulley 6. A pulley 7 is loosely supported on the main-shaft adjacent the fast pulley.

Meshing with the worm 5 is a worm-wheel 8 having a movable section 9 yieldingly urged radially outward to complete the continuity of the teeth on the worm-wheel by a coil-spring 10 pocketed in a socket 11 in the worm-wheel and extending laterally from the movable gear section is a triangularly shaped lug 12 which is engageable by a latch 13 having broad (wear) and narrow (trip) surfaces 14 and 15 the latter of which is notched as indicated at 15'. The latch 13 holds the loose gear section 9 out of mesh with the worm while a bobbin is being filled.

25 When the bobbin however is fully wound the latch releases the gear-section and allows it to move into intermeshing relation with the worm to start a single revolution of the worm-wheel.

30 In axial alignment with the main-shaft 2 is a shaft 16 rotatably supported in a bearing 17 formed integral with a carriage 18 which is provided underneath with a groove embracing a tongue 19 constituting a fixed 35 part of the frame. A handle 19' is provided for manual displacement of the carriage. The shaft 16 has a second rotary clamp-head 4' fixed thereon in opposed spaced relation with the clamp-head 4 on the main-shaft from which the second-clamp-head 4' derives its rotation through a countershaft 20 and suitable gears 201, one of which is wide enough to permit separation of the heads 4-4' without interrupting their rotation.

40 One of the ends of shaft 16 is tapered as shown to center the bobbin when it is initially positioned between the clamp-heads.

45 The rotary clamp-head 4' is displaceable axially to release a filled bobbin and clamp an empty bobbin. For this purpose a pin 21 is secured to the under side of the carriage with its split end embracing a collar 22 fastened to a rod 23 slidably supported in 55 the frame of the machine beneath the carriage. A spring 24 coiled about the rod 23 with one of its ends reacting against an adjustable bushing 25 and the other of its ends pressing against the collar 22 normally urges the axially displaceable rotary clamp-head toward the non-displaceable clamp-head. One end of the rod 23 is located adjacent the worm-wheel 8 in the path of a lever 26 having a lug 27 which is engaged

65 by the cam 28, when the worm-wheel is rotated, to separate the rotary clamp-heads.

70 Preferably, however, as shown in Fig. 18 the end of rod 23 is provided with a pin 29 embraced by the slotted end 30 of a bellcrank 31 whose opposite end 32 is provided with a pin 33 preventing accidental displacement of the coil-spring 34 interposed between it and the tappet arm 35. A lug 36 on the 75 first mentioned arm of the bellcrank is engaged by the cam 28 to effect separation of the rotary clamp-heads as heretofore explained.

80 When, however, the cam 28 in its cycle of operations permits the coil-spring 24 to move the displaceable rotary head toward the relatively fixed head a cam 37 also movable with the worm-wheel is adapted to depress the tappet arm 35 and compress the coil-spring 34 to increase the pressure, transmitted through the bellcrank 31 and pin 29 to the rod 23, with which an empty 85 bobbin is initially gripped.

90 In the lower part of the frame of the machine a rock-shaft 38 is supported on pivot pins 39 with a short arm 40 thereof in juxtaposition to an adjustable tappet lever 41 fulcrumed on the pin 42 in the frame of the machine with a roller 43 on one of its ends in the path of a raised cam 44 suitably secured to the worm-wheel, the opposite end 95 45 of the adjustable tappet arm being adapted to engage the short arm 40 on the rock-shaft 38 and at certain times move it in a counter-clockwise direction, as viewed in Fig. 8, against the force of a spring 46 coiled about the rock-shaft. An adjustable stop in the form of a screw 47 is secured to the rock-shaft and its free end in contact with a fixed portion of the frame limits the outward movement of the short arm 40 under 100 the action of spring 46.

105 In rear of the rotary clamp-heads and fixed on the rock-shaft 38 is a segmental arm 48 having a recess 49 in its front end which registers beneath the discharge end of a chute C when the segmental arm is in a 110 retracted position. The back of the segmental arm 48 is concentric to the axis of the rock-shaft 38 and when the segmental arm advances to position a bobbin between the rotary clamp-heads, the bottom of the 115 chute is closed off and the bobbins sustained therein. The segmental arm is not as wide as the inside distance between the flanges of bobbins so that the bobbins may straddle it. At the rear end of the segmental arm 48 is fixedly secured an arcuate member 50 carrying a thread-eye 51 which being arranged on its free end is adjacent the winding point. The thread-eye 51 is disposed between fixed thread-guides 52 and 53 so that 120 in its movement forward with the segmental arm 48 it increases the length of thread 125 between the fixed thread-guides and thereby

takes up any slack thread that may exist between the winding point and the supply tension 54. The fixed thread-guide 52 is of relatively great length and its apertured end 5 is located so far from the winding point that the thread distributes itself during a winding operation in a manner well known.

A gauge or finger 55 is adapted to rest upon the thread between the flanges of a 10 bobbin being wound and to be displaced by the accumulated thread to trip the latch 13 on a common support therewith and thereby to allow the loose section of the worm-wheel 8 to complete the continuity of its toothed 15 periphery and start the worm-wheel to rotating. The gauge or finger 55 is carried by a horizontally arranged slide 56, Figs. 1, 3 and 9 fitted in a U-shaped groove 57 on the free end of a lever 58 which has secured thereto a strap 59 overlapping a notched portion 60 in the slide 56. Threaded horizontally into the lever 58 is a screw 61 on whose forwardly extending end lock-nuts 62 are provided for refined adjustment in timing the release of the latch 13 carried by the lever 58 and consequent starting of a series of operations. The lever 58 has a tongue 65 arranged to slide in a groove 66 provided in a stationary part of the frame as indicated in Fig. 9 steadyng its movements in a plane about its fulcrum 67 at the right end of the machine. The latch 13, whose form is shown in detail in Figs. 11, 12 and 13, is secured by the screws 68 to the lever 58 adjacent its fulcrum and directly above the axis of the worm-wheel 8. A leaf-spring 69 suitably secured in a vertical position to the frame at one end presses with its other end against the lever 58 and yieldingly urges the gauge or finger 55 in a direction to carry it against the accumulating thread. It is to be noticed that the vertical faces of the tongue and groove 65 and 66 limit the inward movement of the lever 58 and that under no circumstances is it possible for the gauge or finger 55 to obstruct insertion of a bobbin into winding position between the clamp-heads.

As shown in Figs. 1 and 7 and in dotted lines in Fig. 3, an open rectangular thread-guide 70 is fulcrumed at 71 upon the carriage 18 with an arm 72 thereof slotted as indicated to receive a pin 74 fixed in any suitable manner to a stationary part of the machine. Through the wide rectangular opening in the thread-guide the thread passes from the supply to the winding point and when a bobbin is filled and the carriage 55 retracted to release it, the thread-guide is swung to the position shown in dotted lines in Fig. 3 to assist in locating the thread across the face of the axially displaceable rotary clamp-head.

Below and close to the winding point is

arranged a thread parting mechanism preferably in the form of shears one blade 75 of which is stationary and is secured in any suitable manner to the frame of the machine with its cutting edge 76 directly beneath the 70 winding point, and the other and movable blade 77 of which is fulcrumed at 78 upon the stationary blade. The movable blade 77 is provided with a pin 79 which enters a slot 80 in a bar 81 adjustably secured at 82 to a 75 part of the carriage 18. Through the connections mentioned the movable blade is actuated by the displaceable head. At its free end the movable blade is provided with a 80 guard 83. Another guard 84 is screwed to the stationary blade 76 with its free end overlapping the body of the movable shear blade which it spring-presses against the stationary blade to insure thread-severance.

Beneath the winding point and thread parting mechanism and between stationary sections of the frame are suitably secured devices for temporarily holding a wound bobbin after it is dropped by the winding mechanism and while it is being parted from the supply. The devices constituting a tray comprise a fixed section 85, Fig. 9, secured between portions of the frame, and a movable section 86, hinged at 87 to the segmental arm 48 and having upper and lower portions 88 and 89 respectively arranged on opposite sides of the fixed section 85. The upper portion 88 of the lower section is not as long as the lower portion 89 thereof and its front end is bent down to afford a pusher for scraping a wound bobbin from the fixed section 85 on to the lower portion 89 of the movable section of the tray which, by the time the pusher has scraped the bobbin off the fixed section, has advanced far enough in front to hold the filled bobbin. Retraction of the movable section will obviously result in scraping the filled bobbin from off the lower portion thereof against the fixed section 85 as will be clear from an inspection of Fig. 9.

The chute C consists of a pair of T-bars 90 suitably curved as shown in Fig. 2 and supported respectively by pairs of ears 91 and 92 and a skeletonized frame extension 93.

At the upper end of the skeletonized frame extension 93 is located a hopper 14 adapted to contain a mass of empty bobbins. The 120 hopper comprises a base-section 95 and a removable cover-section 96 which is secured thereto by screws. The hopper is cylindrical in form and is inclined to the vertical. The internal lower wall 97 of the cover-section is 125 conical in form, being flared outwardly nearly in parallelism with the conical wall 98 of an annular groove turned in the base-section 95. Together the conical walls 97 and 98 define a substantially U-shaped end- 130

4
less groove which is open internally and is of a width slightly greater than the outside distance between bobbin flanges. The walls 97 and 98 are, at their lowermost portions, substantially tangent to spaced vertical planes. This U-shaped groove communicates with the chute C through an aperture 99 provided in the lowest part of the circular hopper whose axis it will be noticed is inclined to the horizontal.

A shaft 100 is rotatably mounted in the base-section 95 and within the hopper has secured to it a cone 101 whose tapering surface is preferably coincident or nearly so with the inner side 98 of the endless stationary groove. The cone 101 is preferably so tapered with respect to the inclined shaft 100 that its sloping surface adjacent the discharge opening is substantially tangent to the vertical. On the cone 101 is fixedly secured a finger 102 with its concave extremity 103 arranged partly at least within the U-shaped endless groove so as to contact with any empty bobbins that may occupy the groove and lift them past the highest part of the hopper where they are free to gravitate down and out of the discharge opening into the chute.

While any suitable mechanism may be employed to turn the cone agitator 101, it is preferred to turn the cone about one-sixth of a revolution every bobbin winding cycle. To this end a one-way friction drive and ratchet mechanism is suited. Such a mechanism as illustrated in the drawings comprises a ratchet-wheel 104 which is permanently secured to the rotatable shaft 100 in cooperative relation with a spring-pressed pawl 105 pivoted at 106 to the base-section 95 of the hopper. Also on the rotatable shaft 100 is secured a circular disk 107 which is embraced by a strap 108 from which extends radially a sleeve 109 in which latter is housed a spring-pressed pin 110 with a movable abutment screw 111 against which the spring actuating the pin reacts to press the pin against a crescent-shaped friction block 112 confined between a bulged portion 113 of the strap and the disk 107. At one side the sleeve 109 carries a ball-ended pin 114 which is embraced by a socket-ended link 115 whose opposite end embraces a ball-crank-pin 116 on the worm-wheel 8. Downward movements of link 115 do not turn the cone agitator as the tendency of the friction-block 112 to rotate the same is opposed by the spring-pressed pawl 105 but upward movements of the link 115 are not resisted by the pawl 105 and are effective to turn the cone agitator. When a bobbin winding operation is completed and when the loose section of the worm-wheel springs into position completing the continuity of the worm-wheel, the ball-crank-pin is given

a single rotation which results in turning the cone agitator and its finger one-sixth of a revolution. This has been found amply sufficient to keep the chute filled with empty bobbins and eliminate idle operation of the machine.

Preferably but not necessarily a cylindrical housing 117 encases the exposed portions of the rotary countershaft 20 and a shield 118 integral with the housing 117 extends over the exposed portion of the main-shaft 2 and above the worm 5 thereon. Stationary circular housings 119—120 are also provided for the rotary clamp-heads. In front of the tray for temporarily holding the discharged bobbins while the thread is being cut, a section 121 of the frame is removably secured in place by the screws 122 and permits access thereto when desired. In back of and below the winding point a guard or shield 123 is also provided to prevent accidental deflection of a falling bobbin into the path of the transferring arm 48.

Operation.—Supposing the machine is in operation and thread is being wound upon an empty bobbin, when the accumulated thread is of the depth desired, which may be predetermined by suitable adjustment of the jam-nuts 62 carried by the lever 58, the latch 13 is displaced to one side of the triangular lug 12 on the loose gear section 9 and the latter allowed to move into position completing the continuity of the worm-wheel and causing the worm-wheel to rotate. The cam 28, fixed to the worm-wheel, engages the projection 36 and through the rod 23 displaces the carriage 18 sufficiently to allow the filled bobbin to drop from between the clamp-heads onto the tray 85 therebeneath. The outward movement of the carriage 18 also swings the thread-guide 70 to the dotted line position shown in Fig. 3 and at the same time separates the blades 75—77 of the shearing mechanism sufficiently to allow the bobbin-thread to be positioned between the cutting blades by the falling bobbin. While the carriage is being shifted to separate the clamp-heads, the segmental arm is being advanced with an empty bobbin in its recessed forward end to a position between the rotary clamp-heads, the movement of the transferring mechanism being timed to bring the empty bobbin into clamping position immediately after the displacement of the carriage has permitted a filled bobbin to drop. When the transferring mechanism is advancing an empty bobbin to clamping position, the thread-eye 51 fixedly secured to the segmental arm is moved to increase the bend in the thread between the fixed thread-guides 52 and 53 and thereby to take up any slack that may have been unwound from the filled bobbin in its fall. This taking up action insures the lo-

cation across the face of the axially displaceable clamp-head of the thread which extends from the wound bobbin resting on the tray to the remote fixed thread-guide 52 if it has not already been so positioned by the shiftable thread-guide 70 and the guards 83 and 84 of the shear trimming mechanism. When the segmental arm 48 carries an empty bobbin forward the member 86 scrapes a filled bobbin from off the fixed section of the tray onto the lower portion of the movable section of the tray, in doing which it is likely to carry the thread against the guard 84 fixed to the stationary cutting blade.

15 As the cam 28 continues in its rotation and allows the coil-spring 24 to move the displaceable clamp-head toward the non-displaceable clamp-head, the cam 37, if also on the worm-wheel, acts to compress the spring 34 and increase the force with which an empty bobbin is initially gripped. This extra spring-pressure is applied only a short time before and a short time after the bobbin is gripped so as to reduce to a minimum friction due to the end-thrust that would otherwise have to be overcome by the rotary shaft. While the carriage is being shifted and a bobbin is being gripped the movable blade of the thread-cutting mechanism approaches the stationary blade and, by reason of the adjustments provided, it may be timed to cut the thread precisely or nearly so at the time the thread is gripped between the displaceable clamp-head and the bobbin thus reducing to a minimum thread waste. During this return movement of the carriage the thread-guide 70, the segmental transferring arm 48, the thread-eye 51, and the movable section 86 of the tray are all moved to their normal or retracted position. During the return movement of the carriage the crank-pin 116 on the worm-wheel, in its last half of a revolution, acts to carry the cone agitator 101 and finger 102 around about one-sixth of a turn. When the filled bobbin is replaced by an empty bobbin the spring 69 presses the lever 58 and carries the latch 13 again into the path of the triangular lug 12 on the movable section 9 of the worm-wheel. And when all the trains of mechanism have about completed their cycles of movements the latch 13 retracts the movable gear section breaking the continuity of the worm wheel so as to stop its rotation at the end of a single revolution.

The hopper for keeping the chute C filled with empty bobbins is of special construction and peculiarly well suited for handling circular articles. When the hopper is filled with a mass of empty bobbins some of them will find their way into the endless groove in which they occupy a position with their axis or hub transverse the extent of the groove and the peripheral edges of their

flanges resting against the bottom of the groove. In no other position can the bobbins get into the groove. If sufficient quantities of the bobbins do not accumulate in the groove in advance of the stirring finger 102—103 the latter will agitate the mass sufficiently to do so. The stirring finger 102 as before mentioned moves about one-sixth of a revolution each bobbin winding cycle and when it reaches the highest part of the hopper in a position substantially like that shown in Fig. 14, the empty bobbins are free to gravitate around the endless groove or partly across the sloping surfaces of the cone 101 and into the endless groove and finally out into the chute C. In the construction of hopper disclosed it has been found impossible for the bobbins to choke at the exit from the endless groove or to wedge themselves in getting into the endless groove. The cone agitator and the walls of the hopper are so constructed that the weight of the mass of empty bobbins within the hopper is not borne by the empty bobbins that occupy a position within the endless groove.

Having thus set forth the nature of the invention, what I claim herein is—

1. In a device for feeding bobbins, a chute, a hopper comprising a stationary cylindrical receptacle supported with its axis inclined to the vertical and having at its bottom a groove defined by opposed conical side walls spaced apart a distance approximately equal to the axial length of the bobbins to be fed, and a conical bottom wall the lowermost portion of which is apertured to communicate with said chute, and an agitator disposed within said hopper and extending into the space between said conical side walls.

2. In a device for feeding bobbins, a chute, a hopper comprising a stationary cylindrical receptacle supported with its axis inclined to the vertical and having at its bottom a groove defined by opposed conical side walls spaced apart a distance approximately equal to the axial length of the bobbins to be fed, and a conical bottom wall the lowermost portion of which is apertured to communicate with said chute, and a conical agitator the surface of which forms a continuation of the inner conical side wall of said groove, said agitator having stirring means at one side of its axis arranged to extend into the space between said conical side walls and being otherwise clear of extensions entering said space.

3. In a device for feeding bobbins, a stationary hopper having a main cylindrical side wall, the bottom portion of which is flared outwardly in the form of a cone, and a conical bottom wall spaced from the lower conical portion of the main side wall to form a conical groove, said hopper having its axis so inclined to the vertical as to cause

the lowermost portion of said conical groove to be substantially tangent to a vertical plane, a chute communicating with said lowermost portion, and stirring means 5 within said hopper.

4. A device for feeding bobbins or the like including a chute, a hopper for keeping the chute filled with empty bobbins comprising a stationary receptacle provided with 10 an internally open circular groove of a width approximately that of the bobbins and arranged in a plane inclined to the horizontal, said receptacle being provided with an aperture establishing communication between 15 the groove and chute, and an agitator of conical form within the receptacle and having a finger arranged thereon with its extremity rotatable in the groove whereby bobbins in the groove may be carried around 20 the groove until they gravitate into the chute, the inner end of the finger being concaved to facilitate elevation of the bobbins from the lower portions of the groove to the highest portion thereof and to prevent 25 choking in the lowest part of the groove.

5. In a device for feeding bobbins, a chute, a hopper comprising a stationary cylindrical receptacle supported with its axis inclined to the vertical and having at its bottom a 30 groove defined by opposed conical side walls spaced apart a distance approximately equal to the axial length of the bobbins to be fed, and a conical bottom wall the lowermost portion of which is apertured to communicate 35 with said chute, and an agitator disposed within said hopper and extending into the space between said conical side walls, the outermost one of said conical side walls having a minimum diameter substantially 40 equal to the diameter of the cylindrical receptacle and a maximum diameter greater

than the diameter of said cylindrical receptacle.

6. In a device for feeding bobbins, a chute, a hopper comprising a stationary cylindrical 45 receptacle supported with its axis inclined to the vertical and having at its bottom a groove defined by opposed conical side walls spaced apart a distance approximately equal to the axial length of the bobbins to be fed, 50 and a conical bottom wall the lowermost portion of which is apertured to communicate with said chute, and an agitator disposed within said hopper and extending into the space between said conical side walls, said 55 conical side walls being at their lowermost portions substantially tangent to spaced vertical planes.

7. In a feeding mechanism for bobbin winding machines, a mass container comprising a nearly closed internally hollow box having a base section with its upper face in a plane inclined to the horizontal, a rotatable shaft sustained thereby at right angles to its upper face, a cone on said shaft with its 60 base in parallelism with said upper face of the base section, a finger secured to and movable with said cone, said base section being provided with a groove one side wall of which forms substantially a continuation of 65 the sloping sides of the cone, a cup-shaped section secured in inverted position upon said base-section, said cup-shaped section having a flared internal wall defining with the groove in the base section a channel of 70 a depth not less than the diameter of the bobbins, said finger extending bodily into the channel, and means for intermittently rotating the shaft and cone carried thereby.

In testimony whereof, I have signed my 80 name to this specification.

PARK A. HERR.
